BUCKLE

Malkon Chadirjian and Oscar Chadirjian,
Corona, N. Y.

Application June 5, 1937, Serial No. 146,566

3 Claims. (Cl. 24—163)

Our invention relates to a buckle particularly adapted for use as a fabric-covered buckle for clothing.

Buckles for use on garments of all kinds are now frequently covered with fabric, either to match or contrast with the fabric of the particular garment with which the buckle is used. Heretofore the covering of buckles with fabric has been either a slow operation or has required comparatively expensive machines. Some buckles have been covered by wrapping a strip of fabric about the frame, but such an operation is tedious and the finished appearance of the buckle is not always satisfactory. Buckles have also been fabric-covered by the operation of applying a piece of fabric thereto and clamping the same in place. Such operation ordinarily requires rather expensive dies and dies which, in general, fit only one size and shape of buckle. Since buckles are or may be of innumerable desirable shapes, the method heretofore employed for covering the buckles is not universally applicable or is not universally satisfactory.

It is the principal object of our invention to provide a buckle which may be quickly and easily covered with fabric without the use of expensive tools or other paraphernalia.

It is another object to provide a buckle, the frame of which may be easily covered with a pre-formed continuous tube of fabric.

It is another object to provide an improved buckle which may be readily covered with fabric and which is cheap to manufacture, easy to assemble, neat in appearance and serviceable.

Other objects and various features of invention will be hereinafter pointed out or will become apparent to those skilled in the art.

In the drawing which shows, for illustrative purposes only, a preferred form of the invention—

Fig. 1 is a face view of a complete, covered buckle illustrating features of the invention;

Fig. 2 is a sectional view taken substantially in the plane of the line 2—2 of Fig. 1;

Fig. 3 is an isometric view of the buckle frame shown in Figs. 1 and 2;

Fig. 4 is an isometric fragmentary view of a continuous fabric tube to be applied to the frame of Fig. 3;

Fig. 5 is an isometric view of one form of chape to be attached to the buckle frame; and

Fig. 6 is a similar view of a modified form of chape.

In said drawing 5 indicates generally a frame preferably formed of a continuous strip or body

of material bent or otherwise formed into buckle shape, for example, the simple rectangular buckle herein illustrated. The frame 5 may be formed of any suitable material, either metallic or non-metallic, but is preferably formed of some light material of the type of Celluloid. As stated, the frame is preferably formed of a single strip or piece of material and the ends 6—7 of the strip are brought together preferably into abutting relationship with each other, so as to form a substantially continuous buckle frame.

The parts of the frame adjacent the division are secured together preferably by means of the buckle chape employed for securing the belt or other strap to the buckle. In the form illustrated the ends of the strip forming the frame at points adjacent the division are provided with means, such as apertures 8—9, and the side of the frame opposite the division is provided with means, such as apertures 10—11, said apertures being interengageable with suitable parts on the chape.

The chape illustrated in Fig. 5 is a relatively extensible one and may comprise a strip of metal or other suitable material 12, slideable relatively to another strip 13. The strip 13 may have sides 14—14 bent and extending over the strip 12, so that the two strips are slidably or telescopically engaged with each other. The strip 12 may have an upstanding flange 15 to prevent disengagement of the parts 12—13 from each other and the strip 13 may be provided with a bendable tongue 16 which, when the chape is fully extended, may be bent over behind the flange 15, as will be clear from Fig. 2, so as to prevent collapse or shortening of the chape after application to the buckle frame, as will be described.

The chape strip 12 is provided with tongues or projections 11, engageable with the apertures 8—9 of the frame 5. The chape strip 13 is provided with corresponding tongues or projections 40 for engagement with the apertures 10—11. When the frame and chape are to be assembled the chape is shortened, for example, to the extent indicated in Fig. 5, and the projections 17—17 are interengaged with the apertures 8—9—10—11 of the buckle frame. The chape is then elongated by sliding the two parts 12—13 relatively to each other and the tongue 16 then bent over, so as to hold the chape in its elongated position.

It will be noted that the projections 17—17 are of somewhat cam formation, so that the two ends 6—7 of the frame are cammed toward each other when the chape is elongated and the frame thus securely held together.

The chape shown in Fig. 6 is of spring material,

either metallic or non-metallic, and comprises a single strip 18 of about the length of the properly elongated chape shown in Fig. 5. The strip 18 is provided with tongues or projections 17, the same as in the form previously described. When the chape 18 is to be applied to the buckle the chape is flexed, so as to shorten the same, and the tongues engaged with the apertures 8—9—10—11, after which the resilience of the chape will straighten out the latter and cause the frame to be held rigidly, as heretofore described.

The principal utility of a buckle formed as herein described is that it may be readily covered by a continuous tube of fabric, illustrated in Fig. 4. A tube of fabric 19 may be readily made on a sewing machine and then turned inside out, so as to provide a perfectly smooth exterior. The fabric from which the tube 19 is made is preferably cut on the bias, so that its diameter may be decreased by pulling on the tube and thus cause the same to snugly fit the buckle frame.

When the buckle is to be covered with a tube of fabric 19 the ends 6—7 are relatively separated or displaced from each other, such separation or displacement being permitted by the resiliency or give of the material of which the buckle frame is made. The tube 19 is then slipped over one end of the buckle frame and worked completely around the frame and over the opposite end adjacent the division. The tube may then be pulled so as to provide a very snug fit of the latter on the frame and the ends of the tube brought together and, if desired, tied or stitched to each other and the surplus cut off. The chape is then applied to the buckle frame, as heretofore described, and of course the projections or teeth 17 pierce the fabric of the tube 19 and, in drawing the parts of the buckle adjacent the division toward each other, the fabric is quite effectively clamped and a serviceable covered buckle produced.

It will of course be understood that when the buckle is applied to a belt the chape will be covered by the end of the belt, which is ordinarily folded over and sewed about the chape. If de-

sired, of course a buckle tongue may be applied to either of the chapes shown.

It will be seen that we have provided a buckle which is cheap to manufacture and which may be assembled with the chape by a person of practically no skill. But little skill is required to provide a serviceable, very neat appearing covered buckle and the buckle frame may be used indefinitely and covered with different fabric tubes.

It will also be observed that the buckle itself may be made of ornamental form and the surface ornamented so that it may be used without covering but the great utility of our improved buckle is that it may be so readily converted into a covered buckle without tools or other expensive paraphernalia.

While the invention has been disclosed in its preferred form it is to be understood that various changes and modifications may be made within the scope of the invention as defined in the appended claims.

We claim:

1. A buckle, comprising a frame, and a two-part telescopic chape engageable with opposite sides of said frame, for the purpose described. 25

2. A buckle, comprising a continuous strip of material of frame form, the ends of said strip lying closely adjacent each other, a continuous tube of fabric snugly fitting said frame, the ends of said tube of fabric being brought together 30 adjacent the ends of said strip forming said frame, and an attachable chape having means penetrating said fabric tube and engageable with said frame ends for securing said ends of said strip forming said frame together and for holding 35 said fabric tube in place.

3. A buckle, comprising a frame having a division at one side, a tube of fabric fitting over said frame, the ends of said tube of fabric being brought together adjacent the division in said frame, and means for mechanically holding the parts of said buckle and the ends of said tube adjacent said division together. 40
